Patented Sept. 14, 1920.

UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

FUSE FOR AVIATION-BOMBS.

1,352,542.

Specification of Letters Patent. Patented Sept. 14, 1920.

Application filed June 16, 1919. Serial No. 304,658.

To all whom it may concern:

Be it known that I, EUGÈNE SCHNEIDER, a citizen of the Republic of France, residing at 42 rue d'Anjou, Paris, France, have 5 invented a new and useful Improved Fuse for Aviation-Bombs, which invention is fully set forth in the following specification.

This invention has for its object to provide 10 an improved fuse for aviation bombs.

A constructional example of the improved fuse is illustrated in the accompanying drawings wherein the figures show the improved fuse mounted in the base of a 15 bomb.

Figure 1 is a longitudinal section along the axis of the fuse, showing the latter in the rest position.

Figs. 2 and 3 are cross sections respectively on the lines II—II and III—III of Fig. 1.

Fig. 4 is a longitudinal section showing the fuse cocked.

The tubular body of the fuse comprises 25 an element A adapted to be fixed to the bomb B and fitted with a percussion cap carrier C mounted in the center of a partition α .

The detonator D is screwed on the lower 30 end of the said element A.

The percussion cap carrier C is formed with an axial passage c and a branch passage c^1 opening into the said passage. In assembling the fuse, a ball E may be arranged 35 as shown in full lines in Fig. 1, in such a manner as to be clamped between a seat formed on the lower end of the passage c and a seat formed on the upper end of an axial passage f provided in a retarder F that is situated inside the detonator and engaged in the lower chamber a^1 of the element A. A retarding composition f^1 is placed in an eccentric recess in the retarder F. The fuse may be set so as to operate 45 without delay, in which case the ball will occupy an eccentric position such as that indicated in dot and dash lines at E^1 (Fig. 1).

The upper chamber a^2 of the element A forms a lodgment for the striker pellet G which bears with a shoulder upon a spring g kept in tension by a set screw g^1 ; this screw serves also for connecting the element A to the element H of the fuse body. This 55 tubular element H is screwed upon the ele-

ment A and has at its upper end an internal screw-thread h into which is screwed a guide screw propeller I that is fixed in its rest position by means of a pin J. A tail K projecting from the hub of the screw propeller is engaged in the rest position in a guideway formed in the pellet G; it serves by means of its lower end k to immobilize a bolt L which is movable in a chamber G^1 in the pellet G. The head of the bolt projects through the pellet and is held in a recess a^3 in the fuse body A, by compressing a spring l which has a constant tendency to push said bolt into the chamber G^1 .

The bomber takes out the pin J before 70 throwing the bomb.

During the fall of the bomb the resistance of the air causes the screw propeller to revolve. During the unscrewing motion of the screw propeller and up to the instant 75 when the tail K—k has become entirely disengaged from the bolt L, the pellet G is immobilized by the said bolt L. When this disengagement has been completely effected, the bolt L is pushed by the spring l into 80 the chamber G^1 . The fuse is then cocked (Fig. 4). The screw propeller I is ejected from the fuse, being guided in the tube H, up to the moment when it leaves the bomb, by a plate or cross member M fixed on the 85 tail K.

On the bomb encountering an obstacle, the pellet G continues its movement by inertia and the striker strikes the percussion cap N, the flash of which is transmitted to 90 the detonator either with delay, or without delay, according to the position which the ball E is given in setting the fuse.

What I claim is:—

1. A fuse for aviation bombs comprising 95 a tubular body, a detonator secured to the lower part of the tubular body, a retarder in the detonator projecting into the lower end of the tubular body, said retarder having an axial bore and an eccentric recess to 100 contain a retarding firing composition, a cap-carrier mounted in the tubular body above the retarder in spaced relation thereto, said cap-carrier having an axial bore aligned with the axial bore of the retarder to 105 form a direct conduit from the cap to the detonator, said cap-carrier also having a branch bore leading from the cap to the space between the cap-carrier and the detonator to form a passage from the cap to the 110

eccentric recess in the retarder containing the retarding firing composition, a ball normally interposed between the aligned bores of the retarder and cap-carrier to close the 5 direct conduit therethrough, said ball being displaceable to open said conduit, a striker pellet slidable in the tubular body to impinge on the cap carried by the cap-carrier, a spring normally pressing the striker pellet 10 away from the cap-carrier, a bolt movable in the striker pellet to engage the tubular body to hold the pellet against movement in said body, a spring normally pressing the bolt into position of disengagement with 15 the tubular body, and a screw-propeller having a hub screw-threaded into the upper end of the tubular body and provided with a tail normally engaging the bolt to hold the latter in engagement with the tubular body, 20 said propeller rotating through the falling of the bomb to unscrew its hub and to withdraw the tail from the bolt, the free bolt responding to the action of its spring to release the striker pellet so that the latter can 25 impinge on the cap when the bomb strikes an obstacle.

2. A fuse for aviation bombs comprising a tubular body, a cap-carrier mounted in the lower part of the tubular body, a striker 30 pellet slidable in the tubular body to impinge on the cap carried by the cap-carrier when the falling bomb strikes an obstacle, a spring normally pressing the striker pellet away from the cap-carrier, a pin projecting

inwardly from the wall of the tubular body 35 to limit the movement of the striker pellet away from the cap-carrier, a bolt movable in the striker pellet to engage a recess in the tubular body to hold the striker pellet against movement, a spring normally pressing 40 the bolt to disengage the recess in the tubular body to free the striker pellet, a screw-propeller having its hub screw-threaded into the upper end of the tubular body so that the rotation of the propeller through the falling of the bomb will unscrew the hub from the tubular body, a tail on the propeller hub extending into the 45 striker pellet to engage the bolt to hold the latter against the action of its spring in engagement with the tubular body, said tail being withdrawn from the bolt as the hub is unscrewed by the rotation of the propeller, the freed bolt responding to the action of its spring to free the striker pellet so 50 that the latter will be cocked to impinge on the cap when the falling bomb strikes an obstacle, a guide on the tail to guide the same as it leaves the tubular body, and a safety pin extending through the tubular body and 55 the hub of the propeller to be removed preliminary to the dropping of the bomb.

In testimony whereof I have signed this specification.

EUGÈNE SCHNEIDER.
